DESIGN FOR A NECKERCHIEF SLIDE

Bertram A. Rose, Oklahoma City, Okla.

Application November 18, 1944, Serial No. 116,441

Term of patent 14 years

(Cl. D17—10)

To all whom it may concern:

Be it known that I, Bertram A. Rose, a citizen of the United States, residing at Oklahoma City, in the county of Oklahoma and State of Oklahoma, have invented a new, original, and ornamental Design for a Neckerchief Slide, of which the following is a specification, reference being had to the accompanying drawing, forming part thereof.

Figure 1 is a perspective view from one side of the neckerchief slide showing my new design; and Figure 2 is a perspective view from the other side thereof.

I claim:

The ornamental design for a neckerchief slide, substantially as shown.

BERTRAM A. ROSE.
